UNITED STATES PATENT OFFICE.

ST. JOHN VINCENT DAY, OF TERRE HAUTE, INDIANA, AND CHARLES D. MOODY, OF WEBSTER GROVES, MISSOURI.

ELEVATED-RAILWAY PLANT.

SPECIFICATION forming part of Letters Patent No. 470,992, dated March 15, 1892.

Application filed May 12, 1890. Serial No. 351,536. (No model.)

To all whom it may concern:

Be it known that we, ST. JOHN VINCENT DAY, formerly of Westminster, England, but now of Terre Haute, Indiana, and CHARLES D. MOODY, of Webster Groves, St. Louis county, Missouri, have jointly made a new and useful Improvement in Elevated-Railway Plants, of which the following is a clear and exact description.

10 The leading object of our improvement is to provide economically for a higher speed of translation and with more safety and less noise and percussion than is practicable with the existing railway systems, wherein heavy 15 rolling-stock is employed and usually in a position of unstable equilibrium.

Several other features characterize and several other advantages are derived from our improved construction, among which, and 20 without naming them in the order of their relative importance, are the following: Tensile strains rather than compressive predominate throughout the structure; an elevated double line of rail presenting less surface to 25 the wind than hitherto has been practicable; a suspended double line of rail between whose lines the rolling-stock can travel and which lines can be spaced any desirable width apart to provide any desirable width of wheel-base; 30 a suspension-railway having cars whose wheel-base is longer than is the distance between the supports of the suspended lines of rails, enabling the weight of a car to be borne generally more or less upon opposite sides of a 35 rail-support; a suspension-railway whose lines of rails are cables in tension suspended from overhead supports and whose form is preserved by means of cables underneath said rail-cables; auxiliary rolling-stock supports 40 available in the event of the giving way of those cables which are the immediate support for the rolling-stock, and also providing for the renewal of such immediate supports without necessarily replacing the auxiliary supports.

45 Other objects and advantages of our invention will hereinafter appear, all substantially as is hereinafter set forth and claimed, aided by the annexed drawings, making part of this specification.

50 In the drawings the several parts of the invention are shown of necessity more or less

detached from each other. They nevertheless jointly form a system and are operated together.

Figure 1 is a side elevation showing several 55 bays of the improved railway; Fig. 2, a cross-section, and Fig. 3 a plan, of same. These views show the structure in outline only. Figs. 4 and 5, respectively, a side elevation and plan, upon a larger scale, of one of the bays. This 60 bay may be a longer one than some of the bays—for instance, one used in crossing a stream; Fig. 6, a vertical cross-section, upon a still larger scale, of the railway in a double-track form, the section being on the line 66 of Fig. 65 7, which in turn is a plan of the parts of Fig. 7; Fig. 8, a side elevation of the parts of Figs. 6 and 7; Fig. 9, an elevation looking in the opposite direction to that of Fig. 8 and from a point *x*, Figs. 6 and 7; Fig. 10, a detail, being 70 a section on an enlarged scale, on the line 10 10, Fig. 8; Fig. 11, a longitudinal elevation showing the mechanism for producing the tension on the track-cables; Fig. 12, a cross-section on the line 12 12, Fig. 11; Figs. 13 and 75 14, respectively, a side elevation and a plan of a two-story track constructed substantially according to our improvement; Fig. 15, a cross-section, upon an enlarged scale, of the parts of Figs. 13 and 14; and Figs. 16 and 17, 80 respectively, a vertical cross-section and plan of a reinforced cable.

The same letters of reference denote the same parts.

A prominent feature of the design is, as 85 stated, the combination of parts, whereby upon a comparatively economical trackway the trains can be moved safely at a high rate of speed. To this end the track is elevated and composed of a double line of rail, whereby a wide wheel-base is obtained. It is also so constructed that the moving train is carried partly above and partly beneath the level of the two lines of rail, whereby the train is not only in a state of equilibrium, but also 90 one well calculated to resist a lateral wind strain; further, owing to the absence of a flooring between the sides of the railway, no substantial obstacle is presented to an upward movement of the air; further, to enable 95 an elevated railway of the kind under consideration to be economically constructed, as

well as to secure other advantages, it is desirable to build it upon the suspension principle, and to employ cables upheld by supports spaced, in the direction of the length of the road, a considerable distance apart, but at the same time to omit much of the truss-work usually introduced into suspension-bridges for the purpose of stiffening them. At the same time the preferred form of car is one adapted to carry its load so that it is distributed in the direction of the length of the road to an extent considerably greater than is the practice in the railway systems now generally in use, and this feature is best carried out by employing cars whose end trucks or wheels are farther apart than are the track-supports.

In the annexed drawings, A A represent the cables, which constitute the lines of rail upon which the rolling-stock immediately travels.

B B, &c., represent the posts or columns, which, with their foundations b b, constitute the principal supports for the rail-cables A A and other parts of the superstructure connected with the rail-cables.

The cables A A are not attached directly to the posts, but are held in brackets C C C' C', &c., some of which C C are attached to the posts B B and others C' C' to tie-rods D D, which at the upper end d thereof are secured to overhead cables E E and at the lower end d' thereof are secured to underneath cables F F—that is to say, for each track constructed according to our plan there are two lines of posts, two track-cables, two overhead cables, and two underneath cables—and the two lines are disconnected, saving opposite the posts, which, in addition to being placed a fixed distance apart crosswise in the track by reason of their ground connections, may be connected by means of an overhead cross-tie—such, for instance, as F', Fig. 15. With this exception the two lines are disconnected and the track between the two lines is wholly open, permitting the passage of the cars between the lines and offering no obstacle to a wind-pressure in an upward direction. All the cables are in tension, the overhead cables being stretched over sheaves b' b' upon the posts, and between the posts sagging downward, the rail-cables being stretched upon the brackets, as described, and the underneath cables also being in tension, but between the posts being curved upward and strained upward against bearings b² b² upon the posts.

The preferable mode of securing the ends of the various cables will presently be described.

A series of the tie-rods D is used in every bay G of the track, substantially as shown. The cables E F and the tie-rods D are connected, preferably, by passing the cables through eyes d², formed in or upon the tie-rods, and the preferable means of fixing the tie-rods in place is one or more set-screws d³, which are screwed into the eye to bind upon the cable, as shown more distinctly in Fig. 10. The tie-rods D are shortest at the central part of the bay and they increase in length to-

ward the posts, as shown, and they assist in holding the rail-cables A A so that they shall not materially sag between their bearings 70 upon the posts as the load passes along them. The brackets C C' project toward the center of the track, and the rail-cable at each side of the track is made to come sufficiently within the plane of its overhead and underneath 75 cables to enable the train to pass without interfering with the last-named cables.

The posts B are united to their respective foundations b, preferably by means of a tie-rod b⁵, which at its ends, respectively, is united 80 with the foundation and with the post and in any suitable manner and substantially as indicated. The foundation is preferably of concrete of suitable cross-section, and in height varying according to the distance above 85 the ground it is desired to place the post, for it is usually better to have the posts of uniform length and to adjust them to the necessary grade by making the foundations higher or lower, as the case may be.

The track may be single H, as indicated in Figs. 14 and 15, or double H' H', as indicated at Figs. 2, 3, 5, 6, 7, and 12, and it may be two-storied, as indicated at H² H², Figs. 13 and 15.

In crossing an exceptionally-wide ravine or 95 stream—such as I, Fig. 4—the posts B may be higher than at other points along the track. In a two-storied track the same tie-rods D may serve in supporting both the upper and the lower line of rail. In other respects the structure conforms substantially to that of the ordinary bays.

In Figs. 11 and 12 is shown a desirable mode of confining the end of a section of the rail-cables and of producing a constant tension thereon irrespective of changes in the atmospheric temperature. The end a of a section a' of a cable is carried from the adjacent post (not shown) out onto a truss J, over a journaled bearing j' therein, and thence downward 100 and fastened to a shaft j², which is held and adapted to be rotated in a bearing j³, and provided with a weighted arm j⁴, which influences the shaft j² to rotate and wind the cable end upon it, as indicated by the arrow 110 j⁵. By increasing the weight j⁶ upon the arm j⁴ the desired strain can be imparted to the cable-section. The end of the next cable-section is represented at a². It is similarly held and drawn. The line of rail between the ends 115 a a² consists of a rigid rail a³, which is supported on the truss J and fitted to occupy the space between the ends a' a², so as to form with them a substantially continuous line of rail. The truss J rests upon and is anchored 120 to a foundation J', containing a well j⁷ to receive the parts used to confine and tighten the ends a' a².

The ends of the overhead cable-sections can be anchored in any of the customary ways 130 employed for holding the ends of a suspension-cable, or by weighted levers and drums, as shown in Figs. 11 and 12. The ends of the underneath cable-sections can be similarly

anchored. Under conditions such as exhibited in Figs. 4 and 5 the ends of the underneath cable-sections can be suitably held by attaching them to rotatable shafts K, journaled in the posts B and having weighted arms analogous in construction and operation to the parts shown in Figs. 11 and 12.

The rail-cables may be single cables, as shown, for instance, in Fig. 11, or composite, in order thereby that an upper portion upon which the wear principally comes may be renewable without necessitating a renewal of the entire cable. To carry out this feature of the improvement a construction such as shown in Figs. 16 and 17 may be adopted—namely, an upper cable a^{10} and two lower cables $a^{20} a^{20}$, united by means of suitable clamps a^{35} , made in parts $a^{30} a^{30}$, united by means of bolts $a^{35} a^{40}$ to form a composite cable, as shown. When the upper cable a^{10} needs to be renewed, the clamps are loosened, the old cable removed, a new one inserted, and the clamps again tightened to bind the three cables together, as before. The other cables can also be separately renewed. Any other relative arrangement of the cables $a^{10} a^{20} a^{20}$ suitable for the purpose in view may be adopted. The overhead and underneath cables may be similarly made composite, partly to enable the cable parts to be separately renewed and partly to provide an adequate support for the load in the event any one of the cable parts gives away.

It is desirable to provide for the safety of the rolling-stock in the event of its derailment. To this end we provide, substantially as is shown in Figs. 4 and 5, a net-work beneath the span. This net-work can be connected in any suitable manner with the superstructure and arranged sufficiently below the rail-cables to come beneath the rolling-stock, and it may be constructed in any suitable manner to uphold the rolling-stock in the event it is derailed.

We claim—

1. A suspension-railway having an upper suspended cable and a lower upturned cable and whose lines of rail are sustained by vertically-extended supports, which in turn are attached to and connect said upper and lower cables, substantially as described. 50

2. The combination of the posts, the upper cable suspended upon said posts, the lower cable strained upward, and the lines of rail, said lines being sustained by supports extending vertically between and tying and bracing said cables, substantially as described. 55

3. The combination of the posts, the upper cable suspended upon said posts, the lower cable strained upward, and the lines of rail, 60 said lines being sustained by supports extending vertically between and tying said cables, substantially as described.

4. A suspension-railway whose lines of rails are cables in tension supported in part by brackets and in part suspended from overhead supports, whose form in turn is preserved by means of cables underneath said rail-cables, as described. 65

5. The combination of the posts, the rail-cables, the overhead cables, the underneath cables, and the tie-rods having the brackets, substantially as described. 70

6. In combination with the rail-cables, the truss J, the bearings j' , and the shaft j^2 , having the weighted arm, substantially as described. 75

7. The combination of the posts, the underneath cables, rotatable shaft K, tie-rods, and overhead cables, as described.
